METHOD AND A DEVICE FOR GRINDING TWIST DRILLS

Ferenc Erdélyi, 2912 E. 102nd St., Cleveland, Ohio

Filed Mar. 10, 1958, Ser. No. 720,229

Claims priority, application Germany Oct. 2, 1957

14 Claims. (Cl. 51—124)

The invention relates to a method for grinding twist drills by means of a rotating grinding wheel and to devices for carrying out the method. It is to be understood that twist drills also include punches.

The tips of twist drills are ground by hand on manufacture, as a rule nowadays. The teaching of women operators, who are usually employed for this sort of work, is very long and costly and only a small part of the women operators originally employed are finally used for this work. The quality of the tip grinding under these circumstances greatly differs in individual drills and between individual operators, so that the quality of drillings and the drilling times of the drills vary considerably from one another.

Twist drill grinding machines are already known. Of these, substantially only those twist drill grinding machines can be employed which operate according to the inversion method, in which firstly the back cutting surface on one side and then the back cutting surface on the other side of the drill are ground, the drill being inverted in between. Such twist drill grinding machines operating by the inversion method can be used to make accurate back cutting surfaces and satisfactorily disposed transverse cutting edges. The setting up of the drill and the carrying out of the grinding including the inversion of the drill still require considerable time and technical skill, so that such twist drill grinding machines can only be taken into consideration for the individual grinding of large twist drills. For a continuous mass production of twist drills, these twist drill machines operating by the inversion method are not suitable.

In addition to those twist drill grinding machines using a pivot lever, devices are also known in which both cutting edges can be ground without inversion. However, these devices operate fundamentally according to the pivot lever system, in which the twist drill to be ground is made to undergo a planet-like circular movement around the pivot lever axis and, at the same time, a rotary movement about its own axis. Such machines are unsuitable for automatic grinding of twist drills, since the supply mechanisms required would be too complicated.

The invention has the object of providing a method and device for grinding twist drills by the inversion method, in which, with a simpler supply, the drill to be ground is continuously rotated and first one and then the other side are ground alternately in a continuous operation.

The object is solved, in accordance with the invention, in that the drill to be ground undergoes a continuous rotation about its longitudinal axis in synchronism with an intermittent reciprocation about an axis for producing the back cutting edges.

The axis for producing the back cutting preferably crosses that of the drill and lies parallel to the plane grinding surface of the grinding wheel.

Preferably, the axis for producing the back cutting lies a constant distance from the tip of the drill to be

2

ground towards its shank end, and there is imparted to the drill during its back cutting a movement in the direction of its axis towards the grinding wheel, wherein this movement is referred to subsequently as the "back cutting axial movement." It is possible in this way to maintain the grinding wheel plane surface in an invariable location and to secure it despite the twist drill tip not being removed from the grinding wheel plane surface during the back cutting pivot movement.

10 The device for carrying out the method includes a chuck in which the drill is stressed during its continuous rotation about its own axis and the step-wise pivoting about the back cutting axis. This chuck is pivoted, before and after carrying out the grinding, about a further axis for the purpose of loading and unloading the chuck. This further axis is referred to subsequently as the "load and unload axis" and preferably runs parallel to the back cutting axis. During grinding, it is preferable for the drill to pivot about this load and unload axis by a small amount corresponding to the grinding amount, whereas 20 otherwise, and preferably during loading and unloading of the chuck, the back cutting pivoting and the back cutting axial movement of the drill are interrupted or discontinued.

25 The angular position of the back cutting surfaces with reference to the longitudinal axis of the drill and hence also the position of the cutting edges is of particular importance for carrying out the grinding, so that this angular position of the back cutting surfaces is made adjustable according to the invention. This is effected in that the rotation of the drill about its longitudinal axis is disconnectable from the power source and can be carried out independently of its other movement, particularly by hand. This is preferably carried out by means 30 of a planet wheel, suitably a differential drive, whose one driving part is normally at a standstill on continuous drive of the drill about its longitudinal axis, but can be altered in position, preferably by hand, if an alteration of the radial angular position of the drill independently of its other movements is desired, for the purpose of 35 altering the angular position of the back cutting surfaces.

The object is thereby solved in that the necessary planet-like tool movement for the conical tip grinding is divided into three separate movements determined in 40 operative sequence, namely:

- (1) A continuous rotary movement of the twist drill to be ground about its own axis;
- (2) A pivoting movement of about 10° about an axis which coincides with the line of the cutting edges; and
- (3) An axial movement of the drill in order to obtain a cutting edge formation by back grinding.

According to a further feature of the invention, at least 45 one finger, whose axis is inclined, particularly less than 45° , to that of the drill to be ground, against the action of a resilient means, is adjustably mounted in the chuck, so that it can engage in one helical flute of the drill to be ground. In this way, the radial position of the drill is determined in the fully automatic machine.

With a normal twist drill provided with two flutes, two 50 such spring-loaded fingers are provided. They always guarantee an exact disposition of all drills of the same dimensions to be ground. Moreover, the inclined position of the finger to the drill axis has the following basis:

The twist drill is inserted with its shank first in a 55 guide bushing and presses back the two fingers against their springs with its shank, until the opening is so large that the whole of the shank of the drill is let through. If the flutes extend into the region of this finger standing under spring pressure, the finger snaps into the flute and the drill is pushed into the previously determined position by the helical push rod corresponding to the flute 60 pitch of the drill. On the other hand, the two fingers pre-

vent shifting of the drill out of the chuck, since the spring-loaded finger lying under about 45° wedges the twist drill in place.

Further improvements and preferred constructions of the object of the invention are explained in connection with the accompanying drawings, in which one embodiment of the invention is shown simply, the parts not otherwise indicated being shown in the operative position.

In the drawings:

Fig. 1 shows a side view of a grinding machine seen from the front constructed in accordance with the invention;

Fig. 2 shows a view from above the grinding machine of Fig. 1 in the operative position of a drill to be ground;

Fig. 2a shows a view similar to Fig. 2 in the position of the insertion of the new drill to be ground and removal of a prepared ground drill;

Fig. 3 shows a diagrammatic representation of the essential parts of the machine seen from the front;

Fig. 4 shows a diagrammatic representation of the essential parts of the machine seen from the side;

Fig. 5 shows a diagrammatic representation of the essential parts of the machine seen from above;

Fig. 6 shows a view from above of a particularly important part of the machine on a somewhat more accurate and larger scale than those shown in Figs. 3-5 for more detailed explanation of these figures;

Fig. 7 shows a longitudinal section through the upper part of the machine with the chuck for receiving the drill to be ground;

Fig. 8 shows a view from above of the device according to Fig. 7;

Fig. 8a shows a diagrammatic view for illustrating the position of the chuck in the load and unload position;

Fig. 9 shows a section along the line XI—XI of Fig. 7;

Fig. 9a shows an enlarged illustration of the path of movement on several axes given in operation, indicated in Fig. 9, of the device according to the invention on an enlarged scale;

Fig. 10 shows a section along the line X—X of Fig. 7;

Fig. 11 shows a view of the device of Fig. 7 in the direction of the arrow XI of Fig. 7;

Fig. 12 shows a section along the line XII—XII of Fig. 10;

Fig. 13 shows a side view of some of the main driving parts of the machine, partly in section, along the line XIII—XIII of Fig. 14;

Fig. 14 shows a section along the line XIV—XIV of Fig. 13;

Fig. 15 shows a longitudinal section through the driving parts of Figs. 13 and 14 along the line XV—XV of Fig. 14;

Fig. 16 shows a partial section along the line XVI—XVI of Fig. 13;

Fig. 17 shows a partial section along the line XVII—XVII of Fig. 15;

Fig. 18 shows a section similar to Fig. 17, with the additional illustration of a hydraulic control drum;

Fig. 19 shows a development of the curved path of the curved drum for controlling the load and unload pivoting;

Fig. 20 shows a development of the hydraulic control drum of Fig. 18;

Fig. 21 shows a section 1—1 of Fig. 18;

Fig. 22 shows a section on the line 2—2 of Fig. 18;

Fig. 23 shows a section on the line 3—3 of Fig. 18;

Fig. 24 shows a section on the line 4—4 of Fig. 18;

Fig. 25 shows a section on the line 5—5 of Fig. 18;

Fig. 26 shows a section on the line 6—6 of Fig. 18;

Fig. 27 shows a section on the line 7—7 of Fig. 18;

Fig. 28 shows a section on the line 8—8 of Fig. 18;

Fig. 29 shows a section through a drive with a coupling which co-operates closely with the driving parts illustrated in Figs. 13-17;

Fig. 30 shows a section through the drive of Fig. 29 along the line XXX—XXX of this figure;

Fig. 31 shows a section along the line XXXI—XXXI of Fig. 29;

Fig. 32 shows a section through the chuck and the chuck cartridge of the chuck for receiving a twist drill of relatively large diameter;

Fig. 33 shows a section through the chuck and the chuck cartridge of the chuck for receiving a twist drill of relatively small diameter;

Fig. 34 shows a longitudinal section through the device for inserting and removing the twist drill in and from the chuck;

Fig. 35 shows a view from above of the device of Fig. 34;

Fig. 36 shows a front view of the device of Figs. 34 and 35;

Fig. 37 shows a section through the oscillating cylinder for effecting the oscillation movement of the grinding wheel, including a view of the corresponding control valve and the hydraulic ducts as seen in the direction 20 of the axis of the grinding wheel;

Fig. 38 shows a section along the line XXXVIII—XXXVIII of Fig. 37 through the oscillation cylinder and the associated parts thereof seen from above;

Fig. 39 shows a section through the control valve 25 for the oscillation cylinder on the line XXXIXa—f of Fig. 37;

Fig. 40 shows a section similar to Fig. 22 through the control roller for illustrating a modified construction of the drive and control of the oscillation cylinder;

Fig. 41 shows a partial section on the line XXXI—XXXI of Fig. 40;

Fig. 42 shows a development similar to Fig. 20 over the lower part of a control roller modified corresponding to Figs. 40 and 41.

According to Figs. 1-6, two motors 2 and 3 are arranged in a machine frame 1. The motor 2 serves for driving a grinding wheel 4, whereas the motor 3 effects all movements of the twist drill to be ground. The motor 2 drives the grinding wheel 4 via a belt 5 and pulleys 6 and 7. The belt pulley 7 is arranged with the grinding wheel 4 in a pendulum support 9, which is pivotally mounted by means of pins 10, 11 in bearings 12, 13 on the frame 1. This pendulum support 9 is oscillated or moved backwards and forwards by means of a hydraulic piston 14 movable to and fro in a cylinder.

In order to permit disposition of the grinding wheel 4, in the direction of its axis of rotation, the pendulum support 9 is adjustable in the direction of the axis of its bearings 12, 13 the belt pulley 7 being correspondingly long in the axial direction. For this purpose, a manually-operable shaft 16 adjustable by means of hand-wheel 15 is provided in the frame 1, which shaft is connected by means of a screw drive 17 with the pin 10 of the pendulum support 9. For operating the shaft 16 by means of the hand-wheel 15, the pendulum support 9 and hence the grinding wheel 4 can be adjusted in the direction of their axes.

In a manner described and illustrated in more detail below, the drill 18 to be ground is clamped in a chuck, which is continuously rotated by means of the motor 3 in the direction of the arrow 21 of Fig. 4. This chuck and hence also the twist drill, during this rotation provided for the purpose of grinding, also undergo an axial movement in the direction of the axis of the drill caused by means of a cam 19 and also, by means of a cam 20, have imparted to them a pivoting movement about an axis, which approximately intersects the axis of the drill and lies parallel to the plane surface of the grinding wheel, namely perpendicular to the axis of the drill.

This axis is referred to subsequently as the "back cutting axis" and is described in further detail below.

In addition, the drill mounted in the chuck undergoes a further pivoting about an axis which runs parallel to the back cutting axis. This pivoting is carried out essentially for the purpose of advancing the drill in the chuck and removing it after grinding is completed.

The kinds of the various movements of the drill to be ground will be understood more exactly with reference to Figs. 7-12. Corresponding to these figures, a bushing 22 is secured to a support plate 23 by means of screws 24 and is rotatably mounted about an axis A (see Fig. 17) in a bearing 25 in the machine frame. This bushing 22 and hence the support plate 23 are subjected, in a manner described in more detail below, to a backward and forward movement in a predetermined rhythm and consequently each workpiece undergoes a pivoting movement.

A pin 26 is rotatably mounted in the support plate 23 by means of a bearing 27 and projects upwardly above the support plate 23 and is secured with its projecting end in an upper plate 28. A carriage guide 29 is provided on this upper plate 28, along which a carriage generally indicated at 31 is adjustably provided by means of roller chains 30. This longitudinal shifting of the carriage 31 is effected by means of the cam 19 already mentioned against the action of a spring 32 which is supported at one side against the upper plate 23 and at the other side against a front wall 33 which forms a part of the carriage 31. The cam 19 rolls on a curved track 244 of a curved track member 8, which is pivotable about pin 245 for the purpose of the desired back cutting adjustment, by means of two screws 246 which are inserted into the front wall 33.

Upwardly the carriage 31 is enclosed by means of a plate 34 which is rigidly connected to an extension 35. A column 36 is secured to this extension 35. In the rigidly interconnected parts 34, 35 and 36, namely the carriage carrier, a bushing 37 is secured in which a shaft 40 is mounted by means of two bearings 38, 39 which is set in rotation in a manner described in more detail below by means of a universal link 41 and a shaft 42.

The shaft 40 drives a chuck sleeve member 44 by means of a pair of bevel gears 43, which member is rotatably mounted in the column 36 by means of two bearings 45, 46.

A cylinder 47 is provided in the chuck sleeve member 44, in which piston 48 is longitudinally movable, whose two operating chambers 49 and 50 are filled with a hydraulic fluid or can be connected to exhaust. This piston 48 is rigidly connected to a chuck extension sleeve 51 which can be shifted to and fro according to the actuation of the piston 48. The axis of the chuck extension sleeve 51 coincide with that of the drill to be ground. The chuck extension sleeve 51 includes a threaded drilling 52 which (see Figs. 32 and 33) co-operates with a screw thread 53 on an interchangeable intermediate piece 63. At the end of the intermediate piece 63, a chuck sleeve 54 with jaw members 55 is secured, which in known manner has a longitudinal slot 56. These jaws are made conical outside (as shown at 57) and co-operate with a corresponding conical surface of a chuck head 58, which (see Fig. 7) is insertable with a screw 59 into a correspondingly tapped drilling 60 in the chuck cylinder member 44, so that one conical surface 61 of the chuck member is drawn against a correspondingly conical surface 62 of the chuck cylinder member. If, by corresponding hydraulic actuation of the chuck piston 48, the chuck extension sleeve 51 and hence the intermediate piece 63 are moved to the right as shown in Figs. 7 and 32, the jaws 55 of the chuck sleeve move into the conical surface 57 of the chuck head 58 and hence are tightened without clearance and concentrically about the drill 18 to be ground. Whereas the one mounting at the shank end of the drill 18 is formed by the jaws 55 of the chuck sleeve 54, the other mounting is formed by means of a bushing 65, which is interchangeably inserted at the front end of the chuck head 58 with a conical periphery 66. The aperture of this bushing 65 is ground exactly to $\frac{1}{100}$ mm. to the diameter of the drill to be ground. In the chuck head 58 at an inclination of 45° to the axis of the drill to be ground and diametrically opposite to each other, two

fingers 67 are arranged, which are each under the action of a spring 68, which is supported on one side against a cap 69 and on the other side against the finger 67. The cap 69 itself abuts against the conical surface 62 of the chuck cylinder member 44 and hence requires no special securing. By these two fingers, the radial angular position of the twist drill to be ground is determined.

According to Fig. 33, with the drill 18 to be ground of a particularly small diameter, a tube 71 is inserted in the intermediate piece 63 by means of a nut 72. This tube has the purpose of preventing the twist drills after grinding from coming into contact with each other and thus possibly suffering damage. In the embodiment concerned, the back cutting pivot axis lies 17 mm. from the tip of the drill. This pivot axis is provided with the reference B in Figs. 32, 33 and 7 and coincides with the axis of the pin 26 (see Fig. 7).

As already mentioned above, the pivoting of the drill to be ground and hence the whole chuck device takes place about the axis B by means of the cam 20. The cam 19 and the cam 20, as set forth in more detail below, are secured to a common shaft 101, so that they are continuously driven together and brought to a standstill after completion of the grinding. The cam 20 co-operates with a roller 70 which is rotatably mounted on a bolt 74 (see Fig. 12), which is secured to the upper plate 28. The back cutting pivot movement about the axis B is effected against the action of a spring 75, which engages at one end on the upper plate 28 by means of a pin 140 and at the other side by means of an adjustable spring container 141 on a projection 76 of the under plate 23. The bolt 74 for supporting the roller 70 co-operating with the cam 20 is secured to the upper plate 28 by means of a carrier 142.

Similarly to the guide rails 29 of the carriage guide on the upper plate 28, the carriage 31 carries guide rails 143 for co-operation with the roller chains 30. The starting position of the upper plate 28 is determined by a set screw 144, which is inserted into the upper plate 28 and abuts the lower plate 23. The carriage 31 engages with side walls 145, its front wall 133 and with its rear wall 146 over the upper plate 28, so that the lower edges of the side walls 145, the front wall 133 and the rear wall 146 are provided with fillets 147, which lie tightly against the above-mentioned surface of the upper plate 28.

The motor 3, as can be seen in detail in Figs. 1-5 and 13-17, drives the cams 19, 20 and the twist drill about its longitudinal axis and also drives the bushing 22 with the lower plate 23 for carrying out the load and unload 50 pivoting about the axis A. The driving force of the motor 3 is divided between two driving members, of which the first drives the bushing 22 with the lower plate 23, whereas the second rotates the twist drill about its longitudinal axis and the two cams 19, 20. For this purpose, the 55 motor 3 drives a shaft 79 over a belt drive 80 which has two wheels 77 and 78. A worm shaft 81 is driven via a double cardan link 82, 83 and an intermediate shaft 84 from this shaft 79 (see in addition to Figs. 3, 4 and 5, also Figs. 29 and 31). The worm 85 of the worm shaft 81 drives a worm wheel 86 which, together with the worm shaft 81, is inserted in a common housing 87 which is secured to the frame 1 of the machine. The worm wheel 86 loosely rotatably mounted in the housing 87 by means of two bearings 88, 89 is rigidly connected 65 with one part 90 of a dog clutch, whose other part 91 is provided on a disc 92, which is provided by means of a pin 93 with a tubular bushing 94.

A hydraulically actuated piston 96 acts from below on the disc 92 via a steel ball 95 and is adjustably provided in a cylinder 97 which forms one part of a housing 70 87.

The operating space of the hydraulic piston 96 is provided with the reference 98 and can be connected with a pressure medium via a duct 99 or with exhaust.

The shaft 101, for driving the two cams 19, 20,

engages longitudinally and rotatably in the bushing 94 for example by means of a tongue and groove connection 100. Between the lower end 102 of this shaft and the disc 92, a spring 103 is provided in order to effect disengagement of the dog clutch 90, 91. On charging the operating space 98 with the pressure medium, the clutch 90, 91 is engaged and hence the shaft 101 is driven via the bushing 94.

A gear wheel 104 is rigidly connected with the shaft 101 and represents the driven member of a planet wheel or differential drive. The planet wheel carrier of this drive is indicated at 105; in this, two bevel gears 107, acting as planet wheels are loosely rotatably mounted by means of two pins 106. These two planet wheels 107 engage with a bevel gear 108 which lies concentrically to the axis of the shaft 101 and is freely rotatably mounted on it by means of two bearings 109, 110.

The planet wheel carrier 105 is rotatably mounted by means of a bushing 111 on a projection 112 which is secured to the frame 1 of the machine. This planet wheel carrier 105 is constructed at its upper end as a worm wheel 113, which engages with a worm 114, which is loosely rotatably mounted in the frame 1 of the machine. The shaft 115 of this worm 114 projects from the frame 1 of the machine and is provided with a hand wheel 116, by means of which the worm 114 and hence the worm wheel 113 can be rotated by hand.

The worm drive 113 and 114 is self-locking. As long as this worm drive is not rotated by actuation of the hand wheel 116, the planet wheel carrier 104 and hence the pivot pins 106 of the two planet wheels 107 remain in the same position.

The shaft 101 is rotatably mounted at the top in the projection 112. The cams 19 and 20 are secured at its upper end.

As long as the pins 106 are secured, only the bevel gear 107 transmits the rotary movement of the bevel gear 104 to the driven bevel gear wheel 108, which is rigidly connected with a gear wheel 117. This gear wheel engages with a gear wheel 118, which is loosely rotatably mounted on a carrier 119, which is rigidly clamped by means of clamp connection 121 to a column 120, which is secured to the frame 1 of the machine. The inside of this column serves for mounting a shaft 73 to which a gear wheel 122 is secured. Between the gear wheels 122 and 118, a gear wheel 123 is inserted which is likewise loosely rotatably mounted on the carrier 119. These gears can be interchanged for adapting to different gear ratios (punches, 3 and 4 flutes).

The gear wheel 122 is connected with a Cardan link 64 which is driven by way of the above-mentioned shaft 42 and drives the Cardan link 41 (see Fig. 7) of the shaft 40.

If the planet wheel carrier 105 is rotated about the axis of the shaft 101, by means of the hand wheel 116 with the coupling 90, 91 (see Fig. 30) disconnected, with the shaft 101 at rest, i.e. with the cams 19, 20 at rest the drill to be ground hence moves about its longitudinal axis, whereby the angular position of its back cutting surfaces and hence the position of its cutting edges are altered. This can be and preferably is effected with the coupling 90, 91 engaged and hence with the shaft 101 rotating. Before a set of drills can be ground, the exact angular position of the back cutting surfaces can be adjusted in this way by means of the hand wheel 116.

From the shaft 79 not only is the driving connection operated via the intermediate disc shaft 84 of the two Cardan links 82, 83, but also the other driving connection, namely that via the belt drive 124, the belt drive wheel 125 and the belt drive wheel 126. The belt drive wheel 126 is connected with a shaft 128 via a slipping clutch 127, which shaft is mounted in the housing 1 of the machine and drives a worm 129 which engages with a worm wheel 130. The shaft 131 of this worm gear, which is likewise mounted in the housing 1, drives a

curved drum 132 with a control curve or track 133 and also a hydraulic control roller 134. A roller 135 engages in the curve 133 of the curved drum 132 and is freely rotatably mounted on a lever 137 by means of a pin

136, which lever is secured to the bushing 22 which, as already mentioned above, is mounted in the housing 1 for pivotal movement about the axis A. By means of a spring 138, which engages at one end a pin 139 on the lever 137 and at the other side against the housing 1, the roller 135 is urged towards one side of the curved track 133 and hence the play between the roller 135 and the slot in the curved track 133 is taken up.

As already explained, pivoting of the under plate 23 is caused by means of the roller 135 rotatably mounted on the lever 137, which roller is controlled by means of the curved track 133. It appears from the development of the curved track 133 shown in Fig. 19 that the under plate 23 is pivoted about the axis A by 25°. During this pivoting, the dog clutch 90, 91 is disengaged, so that neither is the drill rotated about its longitudinal axis nor are the rear grinding control cams 19 and 20 driven. For the subsequent constructions reference is made particularly to Fig. 6, although Figs. 7-12 are also of relevance. The shaft 40 rotatably mounted in the carriage 31 also takes part in this load and unload pivoting about the axis A, this movement being made possible by the sliding shaft 42 and the two universal links 64 and 41. The engagement of the pair of bevel gear wheels 43 for driving the drill about its longitudinal axis is thus not interrupted. As to the mutual positions to the axes A, B and C, the small illustrations in Figs. 8A and 9A are given for illustrative purposes.

For constructive, but not for mandatory or technical reasons, the axis C lies in the starting position for grinding at each stepwise pivotal movement for producing the rear grinding about 4° 30' from the axis B, displaced toward the connecting line A-B. In each pivotal movement for producing the back cutting at the drill cutting edges, measured at about 9° from the axis B, the axis C oscillates corresponding to the control effected by the cam 20 through each 4° 30' towards the axial connecting line A-B.

After the chuck device has been released by actuation of the operating side 50 of the chuck piston 48, the drill already ground in the previous operation is pushed in the direction of its longitudinal axis from the chuck head towards the rear and a new drill is moved into the chuck head as described further below. As can be seen from the curved path shown in Fig. 19, a curve angle of 35° is necessary for this. Rear pivoting over the under plate 23 about the axis A into the grinding position now occurs, wherein 24° 30' is required and not 25° as appears from Fig. 19. At the beginning of the grinding, the 145° 30' curve angle is taken into account. During this time, a further rotation of the under plate 23 through 30' takes place and hence also of the drill to be ground, which corresponds to a grinding loss of about 1 mm. during the pre-grinding step.

Shortly before beginning the grinding, the clutch 90, 91 is engaged so that the drill is rotated about its longitudinal axis (by means of the shaft 40 and the bevel gear wheel drive 43) and at the same time the back cutting cams 19 and 20 are likewise driven. In synchronism with the rotation of the drill about its longitudinal axis, the upper plate 28 is pivoted by means of the cam 20 about 9° round the back cutting axis B, namely in the clockwise direction as shown in Figs. 6 and 8-10. Moreover, by means of the cam 19 the whole carriage 31 on the upper plate 28 is moved in the same rhythm by a slight amount forwardly in the direction of the axis of the drill towards the grinding wheel. In the embodiment, this back cutting axial movement amounts to 1.5 mm. The control is so provided that in one revolution of the drill to be ground about its longitudinal axis the

two cams 19, 20 undergo two revolutions. In this way, two back cutting surfaces are ground on the drill. A complete revolution of the shaft 131 and hence of the curved drum 132 corresponds to a plurality of revolutions of the drill to be ground. In this embodiment, about six revolutions of the drill to be ground are effected, and hence about twelve revolutions of the shaft 101 to drive the two cams 19, 20, to cause a full revolution of the curved drum 132. As shown, particularly in Fig. 8, the line which the angular position of the drill axis makes lies parallel to the grinding wheel axis; it consequently lies at 90° to the grinding wheel plane surface and goes through the axis A, as also shown in Fig. 5. This angle of 32° gives to the drill a tip angle of 116°.

In the embodiment shown, the transmission ratios are so chosen that the worm wheel 130 and hence the curved drum 132 undergo 3.75 revolutions per minute. At the actual grinding time, a time of 12.2 seconds elapses and, in the travel towards the pivotal movement and for insertion, the time of 3.8 seconds, so that altogether a beat for grinding a drill occupies 16 seconds; in one minute, consequently, there are about 4 beats or operations and four drills of about 10 mm. diameter are prepared. For the rotation of the drill about its longitudinal axis the following quantities hold: In an operation, there are 8.5 revolutions during the whole time or 16 seconds. During the actual grinding time of about 12 seconds, it undergoes 6.5 revolutions, which corresponds to 32.5 revolutions per minute. Corresponding to this number, the chuck head 58 and the shaft 40 are driven accordingly. The shaft 101 for driving the two back cutting cams 19, 20 is however operated at twice the number of revolutions, namely at 65 revolutions per minute.

Correspondingly, the number of revolutions, namely 6.5 revolutions, during the grinding time of 12.2 seconds=1 operation, the drill to be ground is operated upon 13 times during one period at the grinding wheel 4. During the total contact time of 16 seconds, the grinding wheel 4 is moved or oscillated once or preferably several times by means of the hydraulic piston 14, so that during this time the whole width of the plane surface of the grinding wheel is employed.

As will appear particularly from Figs. 34-36, introduction of the twist drill to be ground into the chuck head 58 occurs and also its removal from the chuck head 58 as a prepared twist drill into the intermediate member 63 by means of a hydraulically actuated ram 148. The hydraulic piston for operating this ram is indicated at 149, which is reciprocally arranged in a cylinder 150. This cylinder 150 is secured to a holding rod 151 which is secured to the upper surface of the stand 1 of the machine. The piston rod 152 of the piston 149 projects outwardly. To it is secured by means of an arm 153 the long insertion ram 148. This ram is guided by means of a bearing 154 which is secured to the cylinder 150. Moreover, close to the position which the chuck head takes up at the end of pivoting about the axis A, a guide or guide bushing 155 is provided which is connected to the cylinder 150 in any manner.

On the cover 156 of the cylinder 150 a tubular guide bushing 157 is provided, which is provided externally with a long thread 158. Through a slot 159 in this guide bushing, the arm 153 projects towards the rod 148. A pair of setting nuts 160, 161 are secured on to the thread 158 of the guide bushing 157, which adjustably determine the two end positions of the piston 149 and hence the rod 148. A cylinder 162 is secured to the rod 151 at a normal position, in which a hydraulically-actuated piston 163 is arranged to be reciprocable. The piston rod 164 in this piston actuates a lever 165 on a shaft 166. This shaft 166 drives a corrugated roller 167, which is provided at the lower outlet 168 of a funnel-shaped container 169, which is secured by means of a frame 170 at the upper end of the container 151.

From the outlet 168 of the funnel-shaped container 169 a small chute 171 leads approximately vertically downwards.

The funnel container 169 serves for receiving the prepared, but not tipped twist drills in such a way that the separate drills lie parallel to the axis of the shaft 166. The depth of the funnel container 169 and the guide chute 171 is only slightly greater than the length of the separate drills to be tipped. The corrugated roller 167 is operated when the ram 148 is moved back, in order to facilitate rearward flow of the drills to be ground from the container 169 into the guide chute 171. The guide chute 171, as shown at 172 and 173, is open at both ends in order to allow introduction of the ram 148. The hydraulic ducts for operating the pistons 149 and 163 are, as indicated in Figs. 34-36, directly guided in the cylinder body through the holder 151 and the clamping device 174, so that at this point no outwardly directed guides need be provided. The guide bushing 157 with the two lock nuts 160, 161 is covered outwardly by means of a cap 175.

For operating the clutch 90, 91 (see Fig. 30) only one hydraulic pressure line 99 is employed, from which the operating space 98 is charged. The return guiding 25 of the clutch into the starting position is effected by the spring 103, as soon as the duct 99 is no longer filled with the pressure medium, but is connected to exhaust.

The chuck piston 48 is however operated by the double-sided operating spaces 49 and 50, so that two 30 ducts must be provided. These two ducts, which are connected to the pressure side of the pump and to the exhaust, are (see Fig. 15) provided with reference numerals 176, 177. They enter (see Fig. 15) into a bushing rigidly connected with the frame 1 and from there pass to a control bushing 178, which is rigidly connected with the frame 1 and has corresponding channels 179 and 179a. The reciprocable bushing 22, which is rigidly connected to the under plate 23, has two annular grooves 180 and 181, of which each leads upwardly to an axial channel 182. These axial channels 182 are extended into radial channels 183 which are provided in the under plate 23. From them, the two channels 183 lead to drillings 184, 185 in the pin 26.

Drillings 186, 187 (see Fig. 10) are provided in the upper plate 28, which run parallel to the back cutting axial movement of the drill effected by the cam 19. Tubes 188, 189 are inserted in the drillings 186, 187, which engage adjustably in corresponding drillings in the bushing 37 and are sealed by packings 190. Within 45 the bushing 37, drillings 191, 192 pass from the tubes 188, 189 to annular channels 193, 194, which are each connected by corresponding drillings 195 to an annular channel 196, 197, which are provided in a bushing 198 which is rigidly connected with the column 36. The 50 annular channel 197 is connected by drillings 199 in the cylinder body 44 with the operating cylinder side 50 of the chuck piston 48, whereas the annular channel 196 is connected over drillings 200, which are provided in the cylinder body 44, with the operating cylinder side 55 49 of the chuck piston 48.

In this way, the pressure medium and the exhaust medium for actuating the chuck piston 48 are supplied inside the actual machine in one or other direction, without ducts being connected to the outside. The duct 176 is thus connected in the manner described to the operating cylinder side 50 and the duct 177 with the operating cylinder side 49.

The hydraulic control roller device 134 which, as already mentioned, is actuated by the shaft 131 which also drives the curved drum 132, is composed of a cylinder 201 which is rigidly connected with the frame 1, as can be seen in particular in Figs. 18 and 21-28. In this cylinder 201, a control roller 202 is rotatably mounted in an oil-tight manner, which is provided with 70 a central pressure medium drilling 203 and two eccentric

tric outlet drillings 204, 205 lying diametrically opposite to one another. The outlet drilling 204, 205 discharge into an outlet space 206, which is provided at one end of the control roller 202 and is sealed from the outside by a cover 207. The outlet space is connected via a duct 208 with an exhaust container (not shown) from which a pressure oil pump (not shown) withdraws oil and feeds the pressure oil via a pressure vessel to the devices under pressure as may require to be actuated hydraulically.

Between the cylinder 201 and the control roller 202, a bushing 209 is provided into which the control roller 202 is machined in any suitable manner.

The section of Fig. 28 shows the supply from the pressure vessel (not shown) via a duct 210 to an annular channel 211 in the control roller, which is continually in connection with the pressure drilling 203 via a transverse drilling 212.

Fig. 27 in connection with Fig. 20 shows the control or the clutch 90, 91 shown in Fig. 30. A duct 213 connects the end of the control roller 202 with the duct 99 of Fig. 30. The annular segmental channel 214, during the greater part of the rotation connects the control roller and hence one operating time for the clutch 90, 91 with the pressure oil drilling 203 via its transverse channel 243. The segmental channel 215 however is only very short. It corresponds to a rotation of 61° for a control roller and connects the operating space 98 of the clutch 90, 91 with the outlet drilling 205 only during the time when the drill is pivoted about the axis A into the insertion position and has been pivoted back again.

The sections of Figs. 25 and 26 show the control for the chuck piston 48, Fig. 25 showing the tightening stroke and Fig. 26 the release, in which the duct 176 of Fig. 26 is connected with the operating cylinder side 50 and the duct 177 of Fig. 25 is connected with the operating cylinder side 49. It will also be seen from Fig. 25 that the long segmental channel 216 of the control roller of the operating space 49 is connected during the greater part of one revolution of the control roller, and hence an operating beat, with the pressure oil connection 203 via the transverse drilling 217. During this rotation, the duct 176 and hence the charged operating space 50 are connected via a long segmental channel 218 with the outlet drilling 204. Only during the time of one operation, where the clutch 90, 91 (see Figs. 27 and 39) is disengaged, is the corresponding operating side 50 of the chuck piston 48 connected via the duct 176 and the short segmental channel 219 with the transverse drilling 220 and hence with the pressure oil drilling 203. The drill is thus released, in order to prepare for the movement of the ram 148. During this time, the operating side 49 of the chuck piston 48 is connected via the duct 177 (see Fig. 25) to the short segmental channel 221 and the short transverse drilling 222 with the outlet drilling 205.

From Figs. 23 and 24 is to be seen the control of the to-and-fro movement of the ram 148. The duct 223 of Fig. 24 is connected with the drilling 225 of the cylinder 150 and hence with the operating space 224 of the piston 149 (see Fig. 24), whereas the duct 226 of Fig. 23 is connected with the drilling 227 of the cylinder 150 and hence with the operating space 228 of the piston 149. Fig. 24 shows that the inlet side 224 of the ram piston 149 is connected via the duct 223 and the long segmental channel 229 for the larger part of one revolution with the control roller, and hence an operating time of the outlet drilling 204. This time corresponds to that during which the actual grinding of a twist drill is carried out. During this long time, the operating space 228 of the piston 149, as appears from Fig. 23, is connected via the duct 226 and the long segmental channel 231 with a transverse drilling 232 and hence with the drilling 203. The piston 149 and

hence the ram 148 are thus safely held in their rearward positions by the pressure medium during the axial grinding.

Only during the short time (see Fig. 19, from which it appears that the time of 1.5 seconds corresponds to a 35° revolution of the control roller) when the chuck device is held at rest in the position pivoted about the axis A is the operating space 224 of the piston 149 in connection via the duct 223 and the short segmental channel 230 (see Fig. 24) with a transverse drilling 233 and hence the pressure oil drilling 203. The ram 148 is moved forward, a prepared drill is pushed out from the released chuck head and, at the same time, a drill to be ground is pushed from the outlets 172, 173 of the channel 171 (see Fig. 34) into the chuck head 58. During this time, the operating space 228 of the piston 149 is connected via the duct 226 and the short segmental channel 234 with the outlet drilling 205.

Fig. 21 and Fig. 22 show exactly the manner in which the piston 14 is controlled by the roller 202 for carrying out the oscillation of the grinding wheel 4. The duct 235 of Fig. 22 is connected with one side of the oscillation piston from the ducts 236 of Fig. 21 connected with the other side.

It also can be seen from Figs. 21 and 22 that the oscillation movement is effected with a variable frequency. On inward movement of the oscillation, the duct 235 and the operating space corresponding to it are in connection via a long segmental channel 238 with a transverse drilling 237 and hence with the pressure oil drilling 203. During this time, the opposite operating space is in connection via the duct 236 with a long segmental channel 239 and hence with the outlet drilling 204. In the rearward movement of the oscillation, however, the operating space corresponding to the duct 236 is in connection via the shorter segmental channel 240 (see Fig. 21) with the pressure oil drilling 203 via a transverse channel 241; during this time, the operating space of the oscillation cylinder corresponding to the duct 235 is in connection via a shorter segmental channel 242 with the outlet drilling 205. These relationships are to be seen particularly from Fig. 20, where the appropriate references are applied to the various control channels. The oscillation piston 14 is adjustably arranged in a cylinder 248 which is pivotally mounted about a pin 249 on the frame 1 of the machine. The piston rod 249 engages a transverse rod 250, which is secured by means of a sleeve 251 to the pendulum carrier 9 and serves at the same time to guide the pendulum carrier.

Hydraulic operating spaces 252, 253 are provided at the two sides of the piston 14, which is connected via ducts 254, 255 to the housing 256 of a control valve, which is indicated in general at 257 and is secured to a carrier plate 271 on the frame 1 of the machine.

It has been explained above in connection with Figs. 20 and 21 how the oscillation piston alone is controlled by means of the control roller 202. The already described embodiment has another modified form, in which the grinding wheel and hence the oscillation piston 14 undergo a plurality of oscillations during one operating time and only the pressure medium supply is controlled by the control roller 202. In the housing 256 of the control valve, a rotary disc 258 is rotatably mounted. Outside the housing a lever 259 is secured on the rotary disc, which is provided with a slot 260 in which a pin 261 engages which is secured to one end of a two-armed lever 262. This two-armed lever is mounted by means of a pin 263, which is secured via the carrier plate 172 to the frame 1 of the machine.

An abutment carrier 264 is clamped on the piston rod 249, which has two adjustable abutments 265 and 266. In the path of these adjustable abutments lies the upper arm of the two-armed lever 262. The double-armed lever has a downwardly-convex surface 268 in the region of its lower arm, which can co-operate with a correspondingly

constructed upwardly-convex surface 269 against the action of a spring in the perpendicular direction of movement of a bolt 270, which is adjustably mounted in a support 271, which is likewise connected in any suitable way to the frame 1 of the machine. The two-arm lever 262 abuts adjustably buffered abutments 286 in its end positions.

The duct 254 is connected to the pipe 272 of the housing 256 and the duct 255 is connected to the pipe 273 of the housing 256. Oil under pressure is passed from the pressure source over the already-mentioned control roller 202 and a duct 274 to a pipe 275 of the housing 256 of the control valve. The three pipe connections 272, 273 and 275 are in connection via radial drillings with the central drilling of the housing 256, in which the control valve 258 is rotatably arranged. These three connections lie in a plane in the middle of the housing 256 (as seen in the axial direction). In the same plane lies a connection or pipe 276, which is in communication with the exhaust container and which likewise discharges into the drilling for the control disc 258. The control disc has four spaces 277, 278, 279 and 280 in the region of the plane in which the four connections 272, 273, 275 and 276 lie. The two spaces 279 and 280 are connected together through a radial drilling 282, whereas a radial drilling 282 is provided for connecting the two spaces 277, 278. In known manner, the excess fluid is withdrawn at the sealing surfaces of the member 258 at either side of the spaces 278-280 via channels and ducts 287.

In the position shown, the pressure medium passes from the duct 274 via the connection 275, the space 280, the connection 273 and the duct 250 to the operating space 253, so that the piston 14 is moved to the left as shown in Fig. 37. During this time, the oil flows from the operating space 255 over the duct 254, the connection 272, the space 277 and the connection on the drilling 256 into the outlet container.

After some time, the lever arm 267 moves into the region of the abutment 266. The lever 262 is now moved into its other end position, whereupon by means of the pin 261 and the lever 259 the control disc 258 is pivoted through 90°. The oil under pressure now passes from the pressure connection 275 via the space 280, the connection 272 and the duct 254 into the operating space 252. The piston now moves to the right as shown in Fig. 27. During this time, the oil flows from the right operating space 253 via the duct 255, the space 278, the drilling 282, the space 277 and the drilling or connection 276 into the outlet container.

As will be seen from the above explanation, the operation of the oscillation cylinder is not controlled by the control roller 202. In the embodiment illustrated in Figs. 40-42, the control roller is omitted from a section similar to that shown in Fig. 21. The duct 274 is in connection via a throttle valve (which is not shown or described) with the control roller 202, which in this region is provided with a segmental channel 282 of small cross-section and a segmental channel 284 or large cross-section. The segmental channel 284 of large cross-section is connected via a radial drilling 285 with an axial drilling 203 and hence with the pressure oil source.

At the beginning of the grinding, the duct 274 and the associated operating space of the oscillation cylinder 248 are in connection with the pressure oil source via the segmental channel 284 of the large cross-section. This segmental channel of large cross-section has a length corresponding to the duration of the pre-grinding step, i.e. roughing (see Fig. 19.) On passing over from pregrinding to final grinding (see Fig. 19), the duct 274 is in connection via the segmental channel 283 of small cross-section and the segmental channel 284 of large cross-section and the transverse drilling 285 with the pressure oil drilling 203. The segmental channel 283 of small cross-section effects a throttling of the amount of oil passing therethrough, and hence a slow oscillatory movement of the

grinding wheel takes place on final grinding. This slow oscillation of the grinding wheel is also maintained during insertion of a new drill to be ground and removal of a prepared fine-ground drill, in order to be able to employ the correct position of the grinding wheel. During the rough grinding, however, the oscillation movement of the grinding wheel is more rapid than in final grinding.

By means of the above-mentioned throttle valve, which is provided in the duct 274, the amount of oil can be regulated so that any desired oscillation speed can be achieved.

What I claim is:

1. A method for grinding twist drills by means of a rotating face grinding wheel comprising simultaneously rotating the drill to be ground about its own axis, pivoting the drill about an axis angularly disposed to its own axis in synchronism with said rotation and axially translating said drill toward and from the grinding wheel face in pre-determined synchronism with the rotation and pivoting of said drill thereby producing a relieved cutting edge.

2. A method for grinding twist drills by means of a rotating face grinding wheel comprising simultaneously rotating the drill to be ground about its own axis, pivoting said drill about an axis angularly disposed to its own axis and intersecting the drill rotating axis in synchronism with said rotation and linearly moving said drill axially toward and from the grinding wheel in synchronism with the rotation and pivoting of said drill to produce a relieved cutting edge.

3. A method for grinding twist drills by means of a rotating face grinding wheel comprising simultaneously rotating the drill to be ground about its own axis, pivoting said drill about a first axis parallel to the grinding wheel face in synchronism with said rotation, linearly moving said drill axially toward and from said grinding wheel in synchronism with the rotation and pivoting said drill about a second axis parallel to said first axis to progressively feed said drill toward said grinding wheel thereby producing a relieved cutting edge.

4. In a machine for automatically grinding twist drills, a frame, a grinding wheel rotatably journaled on said frame, carriage means mounted on said frame for pivotal and linear movement with respect to said grinding wheel, means mounted in said frame pivoting and linearly moving said carriage in pre-determined synchronism, a drill support mounted on said carriage, means actuating said drill support for clamping and unclamping a drill therein, magazine supplied feed means mounted on said frame and control means actuating said drill support actuating means and feed means upon said carriage arriving at a pre-determined position to introduce a new drill into said drill support upon completion of the grinding of the previously ground drill.

5. In a machine for automatically grinding twist drills, a frame, a grinding wheel rotatably journaled on said frame, a carriage mounted on said frame for simultaneous, synchronized, rotational, pivoting, linear movement thereto, carriage actuating means mounted on said frame, a drill chuck mounted on said carriage, chuck actuating means opening and closing said drill chuck, drill loading means mounted on said frame adjacent said chuck at one position of said carriage and control means actuating said chuck actuating means and said loading means at said one carriage position to introduce an unground drill into said chuck.

6. In a machine for automatically grinding twist drills, a frame, a grinding wheel journaled on said frame, a support plate rotatably mounted on said frame about a first axis, a swivel plate pivoted on said support plate about a second axis, a carriage linearly slidable upon said swivel plate, a drill chuck mounted on said carriage rotatable about the axis of a drill chucked therein and actuating means mounted on said frame simultaneously rotating

said support plate and drill chuck, pivoting said swivel plate and lineally moving said carriage in relation to said grinding wheel to automatically grind a drill mounted within said chuck.

7. In a machine for automatically grinding twist drills, a frame, a face grinding wheel rotatably journaled on said frame, drill chuck support means mounted on said frame, a drill chuck rotatably mounted on said support means for rotation about the axis of a drill chucked therein, means rotatably supporting said drill chuck on said frame about a first axis, means pivotally mounting said drill chuck with respect to said frame about a second axis parallel to the face of the grinding wheel and means supporting said drill chuck for linear movement in a direction parallel to the axis of the chucked drill.

8. In a machine for automatically grinding a twist drill, a frame, a grinding wheel having a planar grinding face mounted on said frame for oscillation in a direction parallel to said grinding face, means rotating said grinding wheel during said oscillation, a support plate rotatably mounted on said frame about a first axis, a swivel plate pivotally mounted on said support plate about a second axis parallel to the grinding face, a carriage lineally movable on said swivel plate, a drill chuck rotatably mounted on said carriage about the axis of a drill chucked therein and cycled and synchronized actuating means simultaneously pivoting said swivel plate about said second axis, lineally moving said carriage in the axial direction of said chucked drill toward said grinding face and rotating said drill chuck while the chucked drill is in engagement with said grinding face to grind a relieved cutting edge on the drill.

9. In a machine for grinding twist drills as in claim 8 wherein said support plate is rotated about said first axis to a drill chuck loading position at the completion of a grinding cycle, drill loading means mounted on said frame, means actuating said drill chuck upon positioning thereof to said loading position to dechuck the ground drill and means actuating said loading means to introduce an unground drill into said chuck.

10. In a machine for grinding twist drills as in claim 8 wherein drill flute engaging means are mounted within said drill chuck to rotatably orient the chucked drill to said chuck.

11. In a machine for grinding twist drills as in claim 8 wherein said support plate is slightly rotated about said

first axis during the grinding cycle to provide rough and finish grinding operations.

12. In a machine for grinding twist drills as in claim 8 wherein common actuating means are employed for pivoting said swivel plate and lineally moving said carriage and positive drive means interconnect said common actuating means with the actuating means rotating said drill chuck.

13. In a machine for grinding twist drills as in claim 12 wherein said positive drive means includes adjustment means to vary the angular relation of said drill chuck with respect to said common actuating means.

14. In a machine for automatically grinding twist drills comprising a frame, a grinding wheel having a planar grinding face rotatably supported on said frame, means for rotating said wheel mounted in said frame, means mounting said grinding wheel for oscillation in a plane parallel to said grinding face, a support plate rotatably mounted on said frame, first actuating means adapted to rotate said plate, a swivel plate pivotally mounted on said support plate about an axis offset and parallel to the axis of said support plate and plane of said grinding face, second actuating means mounted on said frame for pivoting said swivel plate in pre-determined relation to rotation of said support plate, a carriage mounted on said swivel plate for linear movement thereto, third actuating means mounted on said frame in synchronism with said second actuating means translating said carriage, a drill chuck rotatably journaled on said carriage and oriented thereon whereby the axis of chuck rotation is parallel to the direction of linear carriage movement, fourth actuating means mounted on said frame rotating said chuck about its axis in synchronism with said second and third actuating means, means opening and closing said chuck in response to the rotative position of said support plate and drill feed means mounted on said frame adapted to insert an unground drill into said chuck upon opening of said chuck.
